TUBE FLARING TOOL

Gideon R. Gagne, Kenosha, Wis., assignor to
Snap-on Tools, Inc., Kenosha, Wis., a corpora-
tion of Delaware

Application October 19, 1931, Serial No. 569,582

8 Claims. (Cl. 153—79)

This invention relates to a flaring device and more particularly to a tube-flaring device, although certain features thereof may be employed with equal advantage for other purposes.

5 It contemplates more especially the provision of a portable device for flaring the tube extremities without requiring any appreciable equipment or special facilities.

There are numerous occasions for flaring the 10 extremities of tubes in that replacements are frequently occasioned in automobiles and other installations. In fact, the copper tubing re-storred to in automobiles for establishing communication between the gasoline tank and carburetor serves only to illustrate the far-reaching 15 uses of tubing. Tubing of this character is connected to various instrumentalities by a union or threaded nipple which is mounted thereon for turning relative to a flared tube extremity serving to retain the nipple against removal.

There are numerous occasions for replacing 20 such tubes or inserting a new portion therein, and in consequence thereof it is necessary or at least highly desirable to enable the flaring of the extremities so that an effective connection 25 may be established. The joints must necessarily be fluid-tight, and the effectiveness thereof depends largely on the type of tube extremity which engages the connecting union or nipple. In consequence thereof, it is exceedingly important to provide a uniform and more or less perfect flare on the tube extremity so as to afford a successful 30 joint or tube connection.

One object of the present invention is to simplify 35 the construction and improve the operation of devices of the character mentioned.

Another object is to provide an improved tool for flaring the extremity of tubes and similar devices.

40 Still another object is to provide a novel device for flaring the extremity of various sized tubular conduits.

A further object is the provision of a simple and effective portable device for flaring the 45 extremities of tubular conduits so as to afford a fluid-tight connection therewith.

A still further object is to provide an effective and simple device for flaring the extremities of tubes without entailing much labor or time.

50 Other objects and advantages will appear from the following description of an illustrative embodiment of the present invention.

In the drawing:

Figure 1 is a plan view of a device embodying 55 features of the present invention,

Figure 2 is a sectional view taken substantially along line II—II of Figure 1, and

Figure 3 is a sectional view taken substantially along line III—III of Figure 2.

The structure selected for illustration comprises a circular body member 10 which is preferably split into half-sections 11 and 12 which are complementary to each other for contact along their adjacent surfaces 13. Threaded studs 14, in this instance two, are anchored in the bottom section 12 for projection through correspondingly-shaped apertures formed in the top section 11. Wing-nuts 15 threadedly engage the studs 14 to retain the half-sections 11 and 12 in association for selective contact responsive to turning tight the wing-nuts 15 in the customary manner. A pin 16 is anchored in the bottom section 12 to any suitable radial position so as to register with aperture 17 formed in the top section 11, thereby guiding the half-sections 11 and 12 for accurate registry.

A plurality of bores 17', 18, 19 and 20, in this instance four, are provided radially in the body member 10 so that the diametral line thereof corresponds with the contacting surfaces 13 of the half-sections 11 and 12, thereby placing half of the bores 17', 18, 19 and 20 in both sections 11 and 12 for complementary association in longitudinal alignment. With this arrangement, the bores 17', 18, 19 and 20 are of sectional formation 21 for the reception of tubular conduits.

In consequence thereof, the bores 17', 18, 19 and 20 are of various diameters to correspond with the standard sizes of tubes that are generally used in different situations occurring in commerce, and these are in axial alignment with bores 22, 23, 24 and 25, respectively. The latter-mentioned bores 22, 23, 24 and 25 are of identical size to receive a cylindrical impacting device 26. The impacting device 26 is slightly tapered and has a flared extremity 27 to enable the convenient manipulation and handling thereof. As shown, the impacting or hammer device 26 terminates in a conical tip 28 which corresponds in inclination and configuration with tapered seats 29 formed at the inner orifice of the bores 17', 18, 19 and 20 as defined by a circular aperture 30 provided in the body member 10 so as to be in alignment in both half-sections 11 and 12. In short, the tubular conduit bores 17', 18, 19 and 20 are interrupted with respect to their correspondingly aligned impacting device receiving bores 22, 23, 24 and 25 so that any one of these sets of bores may be utilized at selective 55

times to flare the extremity of correspondingly sized tubing 21.

The tubing 21 is placed in a correspondingly sized bore, in this instance bore 18, with the wing-nuts 15 sufficiently loosened for the free reception thereof. The tubing 21 projects beyond the inner orifice of the bore 18 for a slight distance commensurate with the seat 29 thereof, and the wing-nuts are thereupon tightened to securely 5 clamp the tubing 21. The impacting device or hammer device 26, thereupon is inserted in the bore 23 which is in alignment with the bore 18, and contact is established with the mouth of the tubing 21. A hammer or other tapping device is 10 utilized to strike the extremity 31 of the impacting device 26 so as to deform the extremity of the tubing 21 by flaring such to correspond with the confronting impacting tip 28 and bore seat 29. As a result, a flaring extremity 32 is provided on 15 the tubing 21 so that a nipple or other securing device may be placed thereon for contact and retention by the flaring extremity 32 thereof. In this manner, a flared extremity may be formed on any tubing and the device is portable so as to be 20 utilized in any situation. To enable the more convenient handling of the body member 10, the exterior periphery 33 is nurled in the customary manner. It is to be noted that any number of 25 bores may be provided in the body member 10, and the device may be utilized in a very effective and simple manner without entailing much labor or time.

Various changes may be made in the embodiment of the invention herein specifically described 30 without departing from or sacrificing any of the advantages of the invention as defined in the appended claims.

I claim:

1. In a device of the character described, the 40 combination of a circular body having radially disposed bores of different diameters in said body there being an opening in said body to interrupt said bores, there being tapered seats at the interrupted extremities of said bores in one portion of said body, and a flaring tool member displaceable in the bores of the other portion of said body for the purpose set forth.

2. In a device of the character described, the 50 combination of a circular body having radially disposed bores of different diameters in said body, there being an opening in said body to interrupt said bores, there being tapered seats at the interrupted extremities of said bores in one portion of said body, and an impacting member having a 55 tapered extremity corresponding to said seats, said impacting member being reciprocable in the bores of the other portion of said body for the purpose set forth.

3. In a device of the character described, the 60 combination of a circular body comprising symmetrical sections having radially disposed bores of different diameters in said body, there being an opening in said body to interrupt said bores, there being tapered seats at the interrupted extremities 65 of said bores in one portion of said body, an impacting member having a tapered extremity corresponding to said seats, said impacting member being reciprocable in the bores of the other portion of said body for the purpose set forth.

4. In a device of the character described, the 70 combination of a circular body comprising symmetrical sections and having radially disposed

bores of different diameters in said body, there being an opening in said body to interrupt said bores, there being tapered seats at the interrupted extremities of said bores in one portion of said body, an impacting member having a tapered extremity corresponding to said seats, said impacting member being reciprocable in the bores of the other portion of said body for the purpose set forth, and means for detachably connecting said body sections to grasp tubing in said 10 taper-seated bores.

5. In a device of the character described, the combination of a circular body comprising symmetrical sections and having radially disposed bores of different diameters in said body, there 15 being an opening in said body to interrupt said bores, there being tapered seats at the interrupted extremities of said bores in one portion of said body, and an impacting member having a tapered extremity corresponding to said seats, 20 said impacting member being reciprocable in the bores of the other portion of said body for the purpose set forth, means for detachably connecting said body sections to grasp tubing in said 25 taper-seated bores, and means for guiding the association and disassociation of said body sections.

6. In a device of the character described, the combination with a split metallic body having a plurality of sectional bores provided therein, there 30 being an opening in said body to interrupt said plurality of bores, said bores in one portion on said body each being of different diameters for receiving correspondingly sized tubes, each of said bores of different diameters having tapered 35 seats at the interrupted extremities thereof, said bores in the other portion of said body being of the same diameter, a flaring tool member adapted for removable displacement in the said last named bores of the other portion of said body, and 40 adjustable clamping fasteners for holding tubes in said first mentioned sectional bores in axial alignment with said last mentioned bores for the purpose set forth.

7. In a device of the character described, the 45 combination with a circular metallic body having a plurality of radial bores provided therein, there being an axial opening in said body to interrupt said plurality of bores, said bores in one portion on said body each being of different diameters 50 for receiving correspondingly sized tubes, adjustable means associated with said body for tightly holding tubes against removal from said bores in the last named body portion, each of said bores of different diameters having tapered 55 seats at the interrupted extremities thereof, said bores in the other portion of said body being of the same diameter, and flaring means displaceable in said last named bores of the other portion of said body to cooperate with said tapered 60 seats for the purpose set forth.

8. In a device of the character described, the combination of a circular body having radially disposed bores of different diameters in said body, there being an opening in said body to interrupt said bores, there being tapered seats at the interrupted extremities of said bores in one portion of said body, and flaring means displaceable in said 65 bores of the other portion of said body to cooperate with said tapered seats for the purpose set forth.

GIDEON R. GAGNE.
